(57) **CLAIM**

The ornamental design for a tree-shaped loose fill packing material, as shown and described.

DESCRIPTION

FIG. 1 is a perspective view of a tree-shaped loose fill packing material;

FIG. 2 is a top view of the tree-shaped loose fill packing material;

FIG. 3 is a front view of the tree-shaped loose fill packing material, the back view being identical in appearance as the front view;

FIG. 4 is a bottom view of the tree-shaped loose fill packing material; and,

FIG. 5 is a right side view of the tree-shaped loose fill packing material, the left side view being identical in appearance as the right side view.
